(57) **CLAIM**

The ornamental design for a golf swing training aid, as shown and described.

DESCRIPTION

FIG. 1 is a front perspective view of the golf swing training aid showing my new design as being used with a golfer; FIG. 2 is a front view of FIG. 1 as shown without the golfer; FIG. 3 is a rear view of FIG. 1 as shown without the golfer; FIG. 4 is a left side view of FIG. 1 as shown without the golfer;

FIG. 5 is a right side view of FIG. 1 as shown without the golfer;

FIG. 6 is a top view of FIG. 1 as shown without the golfer; FIG. 7 is a bottom view of FIG. 1 as shown without the golfer;

FIG. 8 is a close up rear perspective view of a head assembly of FIG. 1; and,

FIG. 9 is an exploded view of the head assembly of FIG. 8. The broken lines showing the golfer in FIG. 1 are for environmental purposes only and form no part of the claimed design. The broken lines in FIGS. 1-9 show functional elements that form no part of the claimed design. Applicant notes that the markings on the figures are for shading purposes only, and are not to be considered a part of the design of the present invention. The design shown is not to be limited to any particular size and may be scaled larger or smaller.
